(57) **CLAIM**

The ornamental design for a display package, as shown and described.

DESCRIPTION

FIG. 1 is a perspective view of a display package of the new design, showing a padlock in phantom lines retained on the display package;

FIG. 2 is a front view of the display package of FIG. 1; FIG. 3 is a rear view of the display package of FIG. 1; FIG. 4 is a right view of the display package of FIG. 1; FIG. 5 is a left view of the display package of FIG. 1; FIG. 6 is a top view of the display package of FIG. 1; and, FIG. 7 is a bottom view of the display package of FIG. 1. The portions of the Figures shown in phantom lines are not part of the claimed design, but are for illustration purposes only.
